UNITED STATES PATENT OFFICE.

GEORGE L. FORESTER, OF ASHEVILLE, NORTH CAROLINA.

RAILWAY-CROSSING.

1,244,439.

Specification of Letters Patent.

Patented Oct. 23, 1917.

Application filed January 19, 1917. Serial No. 143,385.

To all whom it may concern:

Be it known that I, GEORGE L. FORESTER, a citizen of the United States, residing at Asheville, in the county of Buncombe and 5 State of North Carolina, have invented new and useful Improvements in Railway-Crossings, of which the following is a specification.

The present invention relates to improvements in track constructions and is particularly directed to railway crossings.

In carrying out my invention it is my purpose to provide a railway crossing with means whereby the treads of the wheels of 15 the rolling stock will be afforded a continuous bearing surface over the said crossing and thus overcome the liability of the wheels sinking between the usual gaps between the rails and the resultant injury to both the 20 wheels and the ends of the rails as well as to relieve the passengers of the train from the shocks and jars thus occasioned.

It is also my aim to arrange upon a railway crossing slideable blocks which may be moved to bring their faces flush with the top and ends of the rails to receive the treads of the wheels and prevent the flanges of the rails contacting with the ends of the rails when a train is passing over the crossing in 30 one direction and for moving the said blocks in an opposite direction to bring the same below the heads of the rails and out of the path of contact with the flanges of the wheels when a train is passing the crossing in a second or opposite direction.

It is a still further object of the invention to arrange upon a crossing a means for bridging the gaps between the rails at the corners of the said crossing which shall 40 comprise gravitationally influenced vertically movable blocks disposed in suitable guides and designed to be engaged and elevated to bring the upper edges thereof flush with the tread surface of the rails by slideable elements which, when arranged below the said 45 blocks, afford supports for the blocks and which when moved away from the blocks will permit of the said blocks gravitating below the tread surface of the rails.

50 It is a still further object of the invention to produce a rail crossing having means for securing the gaps thereof to provide a continuous bearing surface for the treads of the wheels of the rolling stock which shall embody the desirable and essential features of 55 simplicity in construction, cheapness to

manufacture, and durability coupled with accuracy and efficiency in operation.

The essential features of the invention involved in carrying out the objects above indicated are necessarily susceptible of embodiment in various forms of construction without departing from the scope of the invention but certain preferred and practical embodiments are exemplified by the accompanying drawings in which:

Figure 1 is a plan view of a railway crossing constructed in accordance with the present invention,

Fig. 2 is a sectional view approximately 70 on the line 2—2 of Fig. 1,

Fig. 3 is a sectional view approximately 75 on the line 3—3 of Fig. 1, the blocks being illustrated in their elevated position,

Fig. 4 is a detail section approximately 80 on the line 4—4 of Fig. 1,

Fig. 5 is a perspective view of one of the blocks, and

Fig. 6 is a perspective view of one of the 85 slideable elevating members for the blocks.

In the drawings, the numeral 1 designates a railway crossing of the conventional form, comprising two intersecting tracks 2 and 3 respectively. The main rails 2^a of the tracks 2 at the corners of the crossing may be integrally formed with the main rails 3^a of the track 3. The main rails 2^b—2^b and 3^b—3^b have their ends spaced from the respective rails 2^a—3^a of the main tracks and the short or guard rails 2^c—2^c and 3^c—3^c of 90 the crossing are arranged at right angles to each other and are spaced from the rails 2^b—2^b and 3^b—3^b. Short guard rails 2^d—2^d are formed at the ends of the main crossing rails 2^b—2^b and 3^b—3^b, the said short 95 guard rails being spaced from the rails 2^a—3^a of the respective tracks 2 and 3, the said guard rails, of course, extending in the direction of the rails of the main tracks.

The main rails 2^b—2^b, the guard rails 100 2^c—3^c of the crossing, and the intersecting corners of the rails 2^a and 3^a as well as a portion of the short guard rails 2^d—2^d rest upon a frame comprising upper flat metallic plates 4 and vertically disposed I-beams 5 105 connecting the said plates, and the center of the crossing may and preferably is provided with a suitable cover (not shown).

The main rails 2^a—3^a at the corners of the crossing have their inner faces enlarged by 110 thickening the webs of the said rails as indicated by the numerals 6 so that the said

2
 webs are arranged in a line flush with the inner faces of the heads of the said rails, and the said thickened or widened portions 6 are provided with a plurality of spaced 5 vertically arranged elongated slots 7 which are disposed opposite similar slots upon the inner and straight faces of the guard rails 2^a—3^a. These alining slots are adapted to receive anti-frictional members, in the nature 10 of rollers 8 provided upon short shafts or trunnions 9 that extend laterally from the sides of the blocks 10. The block members are of sufficient weight as to be gravitationally influenced, whereby the same will 15 drop below the bearing or tread surfaces of the rails and rest upon the plates 4 heretofore referred to. The slots 7 are so arranged that when the antifrictional members 8 contact with the upper walls thereof, the blocks 10 will be limited in an upward direction whereby the upper faces of the said blocks will be arranged flush with the tread surfaces of the rails.

By reference to the drawings it will be 20 noted that each of the blocks 10 has what I will term its outer face straight, four of these blocks being arranged in a line with the inner faces of the main rails 2^a, and the crossing rails 2^b which are also in a line 25 with the said rails 2^a, while the remaining four blocks 10 have their outer straight edges flush with the inner faces of the rails 3^a and the crossing rails 3^b of the track 2. The referred to series of blocks are adapted 30 to be operated simultaneously in a manner which will be presently described, so that the first referred to blocks when elevated will fill the gap between the rails 3^a and the short rails 3^a, causing a continuous tread 35 surface to be presented to the wheels of the rolling stock traveling upon the track 2 and likewise when this series of blocks is lowered the second referred to series may be elevated to close the gap between the rails 40 3^a and the crossing rails 3^b to provide a continuous tread for the wheels of the rolling stock traveling upon the track 3. The inner edges of each of the blocks is cut angularly from its upper edge inwardly toward 45 its base as indicated by the numerals 11, and the beveled end 11 adjacent to the sides of the block is formed with continuous grooves 50 12—12. Each of the blocks 10, upon the underface thereof is provided with a longitudinally extending groove 13, the walls provided by the said groove being substantially T-shaped as clearly illustrated in Fig. 5 of the drawings.

The plates 4 directly below each of the 60 blocks are provided with elongated slots or openings 14 through which pass the centrally arranged webs or brackets 15 formed centrally upon the lower flat faces of the elevating members 16 for the blocks 10. 65 The elevating members 16 are also in the

nature of flat substantially rectangular blocks and have what I will term their inner ends cut at an angle, corresponding to the inclined ends 11 of the blocks 10, as indicated by the numeral 17, and these beveled ends are provided with outwardly extending ribs 18 that are adapted to aline and to be received in the grooves 12 upon the beveled ends 11 of the blocks 10. The elevating members or blocks 16 upon the upper and 70 flat faces thereof are provided each with a centrally arranged longitudinally extending tongue 18'. The said tongue is T-shaped in cross section so as to be received in the T-shaped groove in the members 13 75 when they have been moved in the direction of the blocks 10 so that when the ribs 18 at the beveled ends of the members 17 leave the grooves 12 of the blocks 10 the T-shaped ribs 18' will enter the T-shaped grooves 13 80 in the said blocks 10, and by this arrangement it will be noted that the members 10 are at all times associated with the elevating members 16. To facilitate the entrance of the ribs 18' into the T-shaped grooves 90 13, the upper horizontal flanges of the said T-shaped ribs adjacent to the beveled ends 17 of the members 16 are cut angularly upon the sides thereof as indicated by the numerals 19, and the thickness of the elevating and supporting members 16 is such that when the same is disposed below the blocks 10, the upper faces of the said blocks will be maintained flush with the heads of the main rails and the guard rails disposed adjacent to the main rails.

In order to properly retain the ribs or brackets 15 within their respective slots 14, I provide the same with transversely arranged pins 20 which are round in cross 95 section and which have journaled thereon anti-frictional rollers 21 which contact with the underface of the plates 4 and which, of course, are of a greater width than the slots 14, it being understood, of course, that the elevating blocks 16 are likewise of a greater width than that of the said slots 14.

Journaled in suitable bearings 21 upon the side members 5 of the frame supporting the members 4 are right angularly disposed 115 shafts 22 and 23 respectively. The shaft 22 extends in the direction of the rails 3^a of the track 3, while the shaft 23 is arranged in a line with the rails 2^a of the track 2. Each of the shafts 22 and 23 away from the center thereof is provided with an offset or crank portion 24 and 25 respectively, and connected with each of the said cranks is a rod 26 and 27 respectively, the rod 26 being extended in the direction of the track 2, 125 the rod 27 being extended in the direction of the track 3, and the said rods 26 and 27 may and preferably do comprise two connecting elements, the connection between the said elements being in the nature of an ad- 130

justable element whereby the rods may be shortened or lengthened as occasion may require. Each of the rods 26 and 27 is pivotally connected to one of the arms of a bell 5 crank lever 28 and 29 respectively, the second arm of each of the bell crank levers having secured thereto a rod or link 30 and 31 respectively, and the said links 30 and 31 also preferably comprise two members which 10 are adjustably connected, and the link 30 is pivotally secured to one of the arms of a bell crank lever 32, the other arm having loosely connected thereto a rod 33 and the rod 33 is secured to the lower end of an 15 operating lever 34, while the link 31 is likewise pivotally connected to an operating lever 35. The levers 34 and 35 may be arranged at any desired position with respect to the crossing, as for instance in a tower 20 house or the like, and the said levers may, if desired, be connected to some suitable signaling device, such as a semaphore (not shown). The shafts 22 and 23 outward of their bearings 21 have centrally secured 25 thereto levers 36 and 37 respectively, and to the opposite ends of the said levers are pivotally connected links 38—38 and 39—39 respectively, the said links being likewise pivotally secured to the webs or brackets 15 dis- 30 posed to the opposite sides of the said levers 36 and 37. By this arrangement it will be noted that when the operating lever 34 is actuated the shaft 22 will be rotated in its bearings, swinging the levers 36—36 con- 35 nected thereto and through the medium of the rods 38—38 move four of the elevating members 16 to cause the same to engage beneath four of the blocks 10, to elevate the said blocks and to close the gap between the 40 rails 3^a and 3^b of the main line 3, or when the said lever 34 is actuated in an opposite direction to bring the elevating members 16 from beneath the blocks 10, to permit of the said blocks to drop by gravity below the 45 tread surface of the said track 3. Likewise when the lever 35 is actuated in one direction the shaft 23 will be turned which, through the medium of the levers 37 connected therewith, will swing the rods 39—39 in opposite 50 directions, causing the elevating members 16 to be brought beneath the remaining four blocks 10 to close the gap between the rails 2^a and 2^b to provide a continuous tread for the wheels of the rolling stock traveling 55 upon the track 2, and, of course, when the said lever 34 is moved in an opposite direction the elevating members 16 will be brought from beneath the referred to blocks 10, permitting the said blocks to gravitate 60 below the tread surface of the rail.

From the foregoing it will be noted that the device as arranged is such that the blocks in both tracks cannot be elevated at one and the same time thereby blocking the 65 crossing in both directions but the reverse

of this is true that by a proper adjustment of the levers both tracks can be left open for passage of trains in either direction exactly as in the case with the present common crossing almost universally in use. 70

It will be further noted that the device as planned of placing blocks between the rails in the manner indicated in no manner weakens or disturbs the present common crossing almost universally in use. 75

Having thus described the invention, what I claim is:

1. In a railway crossing, blocks in the gaps between the rails at the corners of the crossing, anti-frictional guide means for said blocks, slideable means disposed to underlie the blocks to elevate the latter to bring the same flush with the heads of the rails, interengaging elements between said means and said blocks, and actuating mechanism for said means. 80

2. In a railway crossing, angularly disposed main rails and guard rails for the main rails, said main rails having their webs widened at the ends thereof and provided with vertical slots, the guard rails also having slots disposed respectively opposite the mentioned slots, gravity blocks in the gaps at the corners of the crossing, laterally extending trunnions upon the sides of the blocks, anti-frictional rollers upon the trunnions and received in the referred to slots, slideable means disposed to underlie the blocks to elevate the latter to bring the same flush with the tread surface of the rails, 90 and operating mechanism for said slideable means. 95

3. In a railway crossing, gravity blocks in the gaps at the corners of the crossing, guide means for said blocks including anti-frictional elements, slideable members co-engaging with one of the ends of said blocks, means comprising mechanism for actuating the slideable means for bringing the same beneath the blocks to elevate the 100 blocks, and interengaging means between the slots and said slideable means when the said means is brought beneath the blocks. 110

4. In a railway crossing, gravity blocks in the gaps at the corners of the crossing, guide means for the blocks to limit the vertical movement of the said block and including anti-frictional elements, each of said blocks having its outer end inclined, slideable blocks having inclined ends designed 115 to engage with the inclined ends of the first mentioned blocks whereby to guide the slideable blocks beneath the first mentioned blocks, and means comprising mechanism for actuating the slideable blocks. 120

5. In a railway crossing, gravitationally influenced blocks in the gaps at the corners thereof, guide means including anti-frictional elements and limiting the vertical movement of the blocks to bring the same 130

- flush with the treads of the rails or below said treads, said blocks having their inner ends beveled inwardly from their tops to their bottoms and provided with continuous 5 grooves, each of said blocks having its under-face provided with a continuous groove, elevating blocks having inner beveled ends provided with ribs normally received in the grooves in the beveled ends of the first mentioned blocks when the latter are in their lower position, a continuous rib upon the upper face of the elevating blocks designed to be received in the groove in the underface 10 of the first mentioned blocks when the elevating blocks have been moved beneath the first mentioned blocks to elevate the latter, and means comprising mechanism for sliding the elevating blocks.
6. In a railway crossing, gravitatively influenced blocks in the gaps at the corners of said crossing, guide means including anti-frictional elements for limiting the vertical movement of said blocks, said blocks upon their outer ends being inclined inwardly from the top to the bottom thereof, 15 said inclined ends having spaced continuous

grooves, each of said blocks having its bottom formed with a continuous substantially T-shaped groove, a slidable block for each of the first mentioned blocks having a 30 beveled end co-engaging with the beveled end of the first mentioned blocks, when the latter are in their lower position, ribs upon the beveled ends of the slidable blocks engaging in the grooves of the beveled ends 35 of the first mentioned blocks when in such position, a T-shaped rib upon the top of each of the slidable blocks designed to enter the T-shaped groove of the respective first mentioned blocks, and means comprising 40 mechanism for actuating the slidable blocks to bring certain of the same beneath certain of the first mentioned blocks for elevating the first mentioned blocks to close the gaps at the crossing to one of the main 45 lines of the track and for elevating the remaining blocks to close the gap at the crossing to the other main line of the track when the first mentioned pairs of blocks are lowered.

In testimony whereof I affix my signature.
GEORGE L. FORESTER.
